UNITED STATES PATENT OFFICE

2,061,939

VENETIAN BLIND

Samuel Hammer, Brooklyn, N. Y., assignor to
 United Metal Box Co., Inc., Brooklyn, N. Y.,
 a corporation of New York

Application May 18, 1934, Serial No. 726,223

4 Claims. (Cl. 156—17)

This invention relates to improvements in the construction and operation of Venetian blinds.

An object of the invention is to provide, in combination with the raising and lowering cords of a Venetian blind, means for hooking the bottom of the blind to the window sill, or the like, so that a lifting pull exerted on the raising cords, will exert a downward pull on the lowermost slat of the blind and hold the blind taut to prevent it from flapping in the wind.

Other objects of my invention will either become apparent or be specifically referred to in the following description thereof wherein reference is made to the accompanying drawing, in which

Figure 1 is an elevational view of a preferred form of my improved blind, as the same would appear when it is suitably mounted on a window frame.

Figure 2 shows the manner in which the hooking device, shown in the lower left-hand corner of the blind in Figure 1, is secured to a window sill or the like in such a way that an upward pull on the lifting cord will exert, through the lowermost slat, a downward pull on the blind.

Figure 3 shows a modified form of the hooking device shown in Figure 2 and the manner in which the same may be secured to a window sill or the like.

Referring now to Figure 1, it will be seen that my blind comprises a head bar 10 mounted in any suitable manner at the top of a window such for example as by supporting the ends of the bar in brackets 11 and 12. In the example shown, the brackets are fastened at the upper corners of the window frame 13, having a sill 14. A slat 15 is secured to the head bar 10 by means of any suitable supports 16 and 17, depending from the head bar, including trunnions 18 and 19, mounted in the ends of the slat 15, respectively. A series of other slats 21, terminating in a lowermost slat 22, are suspended from the tilting slat 15 by flexible members 23 made of any suitable flexible material, but preferably fabric tapes. The tapes 23 are secured to the edges of the slats 15, 21 and 22 in any suitable manner such for instance as by securing means cooperating with apertures 24 formed in the edge faces of the slats. All of the slats and the head bar are perforated as at 25, see Figure 2, to permit the passage therethrough of raising and lowering cords 26 and 27. The ends of the cords 26 and 27 are fastened to the bottom of the lowermost slat 22 at points 28 and 29 removed from the holes 25 for reasons to be hereinafter described.

Pulleys 30, 31 and 32, mounted in the head bar, are provided to position and guide the cords 26 and 27 when they are pulled from their vertically spaced positions to one side of the window where they pass through a locking device 33 adapted to grip the cords and thereby hold the blind in any desired position, such for example as that illustrated in Figure 1. Hooks 34 are slidably mounted on the raising and lowering cords 26 and 27 between the point of attachment of the cords 10 to the slat 22 and the hole 25 in the slat through which the cords pass upwardly toward the head bar. Eyes 35, with which the hooks 34 are adapted to engage, are mounted in the window sill for reasons to be hereinafter described.

The operation of the blind just described is similar to that of blinds of this general class except that the over-all bundling height of the slats in this case will be considerably less than it would be if ladder tapes were used, in which case the bundling height would be increased by an amount equal to the summation of the thicknesses of the slat-supporting cross-tapes of the ladder tape.

Figure 2, showing the lower left-hand corner of Figure 1 when the blind is in fully lowered position, illustrates the manner in which the bottom of the blind may then be secured to the window sill or the like and drawn taut to prevent it from flapping in the wind. One of the advantages of this means of fastening the blind is that after the hook 34 is secured to the eye 35 an upward blind-raising pull on the cord 26 will exert a downward pull on the slat 22 as indicated by the arrows. The extent to which the slat 22 may be pulled downwardly is governed by the length of the tapes 23 upon which all the slats are hung from the topmost slat 15.

I illustrate in Figure 3 a modified form of hooking device comprising an eye 90 adapted to slip on the cord 26 in a manner similar to that of the hook 34 just described. The eye 90 is provided with an enlarged head 91 adapted to cooperate with a slotted fixture 92 which is secured to the window sill in any suitable way. It will be understood that the end 28 of the cord 26 is provided with a knot or washer or otherwise suitably secured to the slat 22 such for instance as by being fitted into a slotted fixture having a construction similar to that of the fixture 92 above described.

While I have described what seems now to be the preferred embodiment of my invention, it is conceivable that various modifications in the configuration, composition and disposition of the component elements going to make up my invention as a whole, as well as in the selective com-

bination and application of the respective elements, may occur to those skilled in the art, and no limitation is intended by the phraseology of the foregoing description or illustrations in the 5 accompanying drawing.

What is claimed is:

1. A Venetian blind comprising a series of flexibly connected slats terminating in a lowermost slat, and flexible raising and lowering members 10 extending through all said slats and connected to the bottom of the lowermost slat, in combination with hooking means slidably secured to said raising and lowering members at a point on said members between the connection of said 15 members to the lowermost slat and that portion of said members which passes upwardly through said slat, and means for connecting said hooking means to a fixed point below said lowermost slat, whereby a raising pull on said flexible members 20 will exert a downward pull on said lowermost slat.

2. A Venetian blind comprising a series of flexibly connected slats terminating in a lowermost slat, and flexible raising and lowering members 25 extending through all said slats and connected to the bottom of the lowermost slat, in combination with hooking means slidably secured to said raising and lowering members at a point

on said members between the connection of said members to the lowermost slat and that portion of said members which passes upwardly through said slat.

3. A Venetian blind comprising a series of flexibly connected slats terminating in a lowermost slat, and flexible raising and lowering members extending through all said slats and connected to the lowermost slat at a point spaced from that at which said flexible members pass through said slat, in combination with means slidably connecting to a fixed point below the lowermost slat that portion of said raising and lowering members disposed between their connection to said slat and the point at which said members pass therethrough whereby a raising pull on said flexible members will exert a downward pull on said lowermost slat. 5 10 15

4. A Venetian blind comprising a series of flexibly connected slats terminating in a lowermost slat, and flexible raising and lowering members for said slats connected to the lowermost slat, in combination with means slidably connecting to a fixed point below the lowermost slat a portion of said raising and lowering members whereby 20 25 a raising pull on said flexible members will exert a downward pull on said lowermost slat.

SAMUEL HAMMER.
